TRIMMER AND GAGE FOR ARC-LAMPS.

1,013,409.

Specification of Letters Patent.

Patented Jan. 2, 1912.

Application filed December 24, 1909. Serial No. 534,854.

To all whom it may concern:

Be it known that we, ABBOT A. Low, a resident of Horseshoe, St. Lawrence county, and HARRY HERTZBERG and MAURICE J. WOHL, residents of the city of New York, borough of Brooklyn, county of Kings, State of New York, citizens of the United States, have invented certain new and useful Improvements in Trimmers and Gages for Arc-Lamps, of which the following is a specification.

This invention relates to an implement for use in manipulating and replacing the carbons of arc lamps, particularly arc lamps having an upper and a lower carbon in vertical alinement. In such lamps, when the carbons are to be renewed, the remaining portions of the carbons are removed from their holding devices, a new, long carbon is inserted in the upper holding device, and the remainder of the old upper carbon, if broken off to the proper length, may be inserted in the lower holding device, to serve as a new lower carbon. It is customary to grasp the new upper carbon in the hand while pushing it to uppermost position and seating it in its holding device; but this is not a convenient operation, inasmuch as by the time the carbon has reached the uppermost position, whence it is to feed downward as it burns away at the lower end, there is such a small amount of the carbon projecting below the bottom plate of the lamp, that it is difficult to hold the carbon and properly seat it. Breaking off the old upper carbon, to make a new lower carbon, also presents some difficulty in the matter of getting the new carbon of the proper length.

The object of the present invention is to produce a tool or implement whereby the new upper carbon may be easily pushed into the lamp casing to uppermost position and seated in its holding device, and whereby the old upper carbon may be easily broken off to the exact length suitable for the new lower carbon.

Other minor objects of the invention will become apparent as the specification proceeds.

The accompanying drawings disclose a suitable form of tool embodying the invention, which may, however, be embodied in numerous other, apparently differing forms.

Figure 1 is a vertical sectional elevation of an arc lamp, with irrelevant parts

omitted, showing the tool in the act of seating the new upper carbon; Fig. 2 is a longitudinal section through the tool, a portion of the stem thereof being broken away for convenience in illustration; Fig. 3 is a view showing the tool with an old upper carbon therein, preparatory to being broken off to make a new lower carbon; Fig. 4 is a sectional view of a portion of the upper end of the tool, showing a modification thereof.

In Fig. 1 is illustrated in skeleton form an arc lamp, in which the numeral 1 indicates the casing, 2 the bottom plate, 3 vertical guiding and connecting rods, 4 the vertical upper carbon, carried by any suitable device, as an insulating block 5 slideable on the rods 3 and provided with a split tube, or resilient or frictional holder 6, 7 a bracket depending from the plate 2 for supporting the lower carbon, and 8 a suitable holder for the lower carbon. This holder 8 may consist of a tube externally threaded, slotted downward from its upper end, provided with a turning head 9 projecting below the bottom of the bracket, 7, and adapted to be screwed into an upward tapering, threaded opening formed through the bottom part of said bracket, in vertical alinement with the upper holder 6. When the holder 8 is screwed upward, with a carbon therein, the carbon is tightly clamped; and when the holder 8 is screwed downward, it is allowed to spread, to release the carbon for removal; all of which will be readily apparent. The parts of the lamp are not claimed herein.

The tool, in its preferred embodiment, comprises a handle 10, having a cup 11 at the outer end thereof, and an annular flange 95 or guard 12 at the base of the cup, a rod or stem 13, preferably metal, mounted in the handle and projecting centrally outward from the bottom of the cup 11 to a considerable distance beyond the rim thereof, and a measuring and holding tube 14 mounted in the handle and opening at the rear end thereof. The stem 13 is designed to be held in a vertical position and inserted upward through the holder 8, after removal of the lower carbon therefrom, as illustrated in Fig. 1, for the purpose of pushing the new upper carbon into place. Better to fit it for this purpose the upper end of the stem 13 may be recessed, as indicated at 15 in Fig. 110

2, or the construction shown in Fig. 4 may be used. In this latter form the stem 13' is recessed as shown at 18 and a centering pin 19 inserted. In this operation, the cup 11 receives the lower, headed end of the holder 8, enabling the rim of the cup to abut against the bottom of the bracket 7; and the rim of the cup is preferably protected by a metal shell 16, forming the inner wall of the cup and projecting forward beyond the outer wall, which is part of the handle, the latter being preferably of wood. In this operation, also, the guard 12 protects the hand and at the same time renders it easier to effect the upward thrust of the tool.

The measuring and holding means 14 is in the form of a rigid metal tube, as illustrated, inserted in a longitudinal bore in the handle and projecting beyond the rear end thereof. The length of the bore of this tube is exactly the length desired for the new lower carbon; hence, the old upper carbon, which is too long for the lower carbon, when placed in the tube 14, projects beyond the end thereof, and this projecting portion may be easily broken off, as by means of pliers. The stem 13 may be secured in the forward end of the tube 14, as by a rivet or pin 17. The cup 11 plays an important part in the operation of seating the new upper carbon. The stem 13 is of such length that when the rim of the cup, that is to say, the edge of the shell 16, contacts with the under side of the bracket 7, the block 5 has engaged and is held against a suitable stop which determines the uppermost position thereof, and the carbon is fully seated in the holder 6. Were the handle of the tool to abut against the bottom of the holder 8, instead of the bracket, this exactness of positioning would be impossible, since the holder 8 being a movable tapered clamping device would at different times be in different positions due to variations in size of the carbons.

Thus, either the carbon would not be sufficiently elevated and seated, or there would be opportunity for the person manipulating the tool to break something by endeavoring to push the carbon higher than would be proper. With the construction illustrated,

the person using the tool is left in no uncertainty. If he encounters resistance before the shell 16 touches the bottom of the bracket, he can be assured that the cause is merely friction somewhere, as the carbon fitting rather tightly in its holder, and knows that he should continue to push the tool upward until the rim thereof contacts with the bracket.

What is claimed as new is:

1. A device for replacing carbons in an arc lamp, comprising a handle having a cup shaped portion at one end, and a rod mounted in said handle and projecting centrally outward from the bottom of said cup shaped portion to a predetermined length beyond the outer edge thereof, the outer end of said rod being recessed to receive the end of the carbon. 65

2. A device for replacing carbons in an arc lamp, comprising a handle having a cup shaped portion at one end, a stop positioned adjacent said cup shaped portion of said handle and projecting beyond the outer edge thereof, and a rod mounted in said handle and projecting centrally outward from the bottom of said cup shaped portion to a predetermined length beyond said stop, the outer end of said rod being recessed to receive the end of the carbon. 70

3. A device for replacing carbons in an arc lamp, comprising a handle having a cup shaped portion at one end, a cylindrical stop positioned in said cup shaped portion of said handle and projecting beyond the outer edge thereof, and a rod mounted in said handle and projecting centrally outward from the bottom of said cup shaped portion to a predetermined length beyond said stop, the outer end of said rod being recessed to receive the end of the carbon. 80

Signed at Brooklyn, N. Y., in the county of Kings and State of New York, this 26th day of November, 1909.
